TRANSMITTING SYSTEM

Clarence W. Hansell, Port Jefferson, N. Y., assignor to Radio Corporation of America, a corporation of Delaware

Application March 26, 1931, Serial No. 525,419

15 Claims. (Cl. 250—17)

It has been common practice prior to my present invention to control the frequency of radio frequency transmitters by means of relatively low power, lightly loaded master oscillators, the 5 outputs of which were amplified through a chain of radio frequency amplifiers to the power desired for transmission. In this previously developed system the conditions for holding the frequency of the master oscillators constant could be obtained more easily and economically than would be the case if the oscillations were developed directly in the vacuum tubes which produce the power to be radiated from antennæ. A system of the latter kind has been developed for high frequencies by the British Marconi Company and is known as the "British Beam System".

In the United States a method for maintaining master oscillators much more constant in frequency than had been possible previously was invented by W. G. Cady and is disclosed in his United States Patent 1,472,583. This method of Cady's employs a piezo-electric crystal and results in a great improvement in frequency control. However, it is subject to limitations in that 25 its constancy is diminished at the higher frequencies and the amount of power obtainable from the crystal oscillator is small.

The first limitation is removed by operating the crystal oscillator at relatively low frequency and 30 increasing this frequency by vacuum tube frequency multipliers. A method for doing this is disclosed in U. S. Patent 1,771,375 of I. F. Byrnes. At the beginning of the development of high frequency transmitters the method described by 35 Byrnes was extended to the use of several similar stages of vacuum tubes each operating as a frequency multiplier and resulting in a final output at one of the higher harmonics of the crystal frequency. This resulted in a great improvement 40 in frequency stability through the use of a relatively low frequency crystal even though the output frequency of the transmitter was much higher than any previously used for high power, long distance, communication.

45 In this type of transmitter the frequency multipliers were all low power tubes of the same size and type so that there was no increase of power in the successive frequency multiplier stages. The output from the last frequency multiplier was amplified by a chain of vacuum tube 50 amplifiers, all operating at the same frequency, to the final power level required for the antenna. In this case the amplifying system followed the previously established practice used in master oscillator-amplifier transmitters of the type used 55

in the British Beam System. The main difference was that the conventional master oscillator was replaced by the combined crystal oscillator and frequency multipliers.

Although this method of constructing and operating a transmitter was an improvement over any previously used methods, yet, at high frequencies, the circulating currents through the dielectric capacities of the tubes caused losses which reduced the amplification and troubles 5 were experienced from undesired spurious oscillations. These spurious or parasitic oscillations were caused by energy feed back from output to input circuits of amplifier stages and from high power stages to lower power stages. The adjustments required to eliminate these undesired oscillations were critical at high frequencies and difficult to maintain over long periods.

To eliminate these difficulties while at the same time reducing the number of stages required for 20 a given output is one of the more important objects of my present invention.

In accordance with my invention I change the transmitter, previously mentioned, to eliminate most of the low power frequency multiplying 25 stages and I use a new system in which the successive intermediate stages of amplification work at successively higher power levels, and, most important, the amplifier stages act as frequency multipliers. Thus, I combine amplification 30 and frequency multiplication in the successive stages of an amplifier system.

After this is done the earlier stages of the amplifier work at lower frequencies where they are 35 more efficient. Also the input and output circuits of each intermediate amplifier stage are tuned to different frequencies so that the feed back from output to input circuits causes little current in the input circuit because of its lack of tuning to the frequency of the energy fed 40 back. Likewise the feed back of radio frequency energy from any stage of amplifier to previous stages is very greatly reduced because of the wide differences in frequencies to which the amplifier circuits are tuned. Consequently, there is a 45 marked freedom from parasitic oscillations and an ease of control and operation borne out in transmitters actually built incorporating the present invention never before approached in an amplifier system for high radio frequencies. 50

In my present system of frequency multiplication at increasing power and also in the system of frequency multiplication at substantially constant power, I have obtained a still further improvement in operation by the use of capacity 55

neutralization and harmonic regeneration as previously described in my U. S. application, Serial Number 177,505, filed March 23, 1927, which resulted in U. S. Patent 1,878,308.

It is a further object of my present invention to combine the use of tubes with four or more electrodes with my system of multiplying frequency and increasing power in the same successive stages of an amplifier system; for, I have found that tubes with more than three electrodes may be used in my frequency multiplier-amplifiers to excellent advantage. Transmitters are now in use employing tubes with two grids in which one grid serves to shield the control grid from the anode and, the addition of the screen grid, which may be kept substantially at zero radio frequency potential, together with appropriate circuit shielding, serves some of the purposes of the capacity neutralization in my Patent 1,878,308 with the advantage that no neutralizing adjustment need be made by an operator and the probability of inefficiency due to human error is greatly reduced.

In my transmitting system it is possible to use any or all stages of amplifiers as frequency multipliers but where expediency in design makes it desirable, I prefer to use some stages as amplifiers without change of frequency. Thus I normally prefer to make at least the last stage an ordinary amplifier since the last stage amplifier determines the final transmitter output so that it is important to obtain as much power as possible from it. Also the power efficiency of the last stage is a large factor in determining the overall efficiency of the transmitter, and, if the last stage were used as a frequency multiplier it would be necessary to make some sacrifice in power output and efficiency. I may use the last stage for amplification only without much danger of parasitic oscillations, if I employ screen grid tubes in the last stage or three electrode tubes with capacity neutralization together with other features essential to good electrical and mechanical construction. I have found it expedient in fulfilling certain requirements to make one or more of the earlier stages act as amplifiers without frequency multiplication. For example I have used an ordinary amplifier immediately after the crystal because by doing so I could lighten the load on the crystal circuit to obtain greater constancy of frequency.

In some cases I have provided switching and tuning means to permit changing various stages to make them operate as amplifiers or frequency multipliers of various ratios for the purpose of changing frequency and a number of transmitters which I made embodying this feature are now in commercial service. For a more detailed description of the method reference may be had to my U. S. application, Serial Number 189,162, filed May 5, 1927.

I have also found that it is undesirable to operate a number of tubes in parallel because of practical difficulties in arranging them so that all will have like conditions. At high frequencies, for example, it is very difficult to obtain equal effective inductances in the grid leads, a condition which must be obtained to make each tube take its proper share of load. Parallel tubes are also subject to the possibility of very high frequency parasitic oscillations through the effective inductances of the connections to the tubes. To reduce these difficulties I prefer to use two tubes or groups of tubes in what is known as the pushpull circuit when maximum power is desired

from any stage of amplifier. At the same time, for purposes of economy, I prefer to use a single tube in all stages where the type of tube and the required power level permit it. Consequently it is a further object of the present invention to provide a method and means for coupling single tube stages to pushpull stages and pushpull stages to single tube stages as may be required for greatest economy when particular types of tubes must be used to meet particular requirements of construction. Preferably, according to my invention, I use single tube frequency multipliers and amplifiers followed by pushpull amplifiers.

A still further object of my invention is to improve the stability of operation of vacuum tube amplifier and frequency multiplier systems to make them less subject to the effects of power supply voltage variations and at the same time I protect the vacuum tubes from destructive currents. Briefly, I do this by employing the combination, for electron discharge devices, of a fixed biasing potential and a potential obtained by passing rectified grid current through a grid leak resistance.

It is characteristic of vacuum tube frequency multipliers and high efficiency amplifiers that the relative values of grid bias and radio frequency excitation potential must be rather critically adjusted. If an operator, while making adjustments, of the power supply voltage causes a variation above or below normal in radio frequency output from any stage then the excitation and the efficiency and output of the next succeeding stage is adversely affected. I may make the biasing potential increase and decrease in accordance with the excitation in a manner to hold relatively constant output and efficiency by employing grid leak bias.

However, when this is done, if for any reason the master oscillator, or any intermediate stage fails to function, so that there is no excitation on any stages, their grid bias falls to zero. In this case the tubes are subject to excessively high and destructive anode currents and losses which endanger the lives of the tubes. Overload protection on the power supply will not entirely remove this danger because the input currents, controlling overload protective devices, under this condition may not exceed the normal input while the energy dissipation in the tubes is greatly increased due to loss of output. In cases where the input currents would be sufficiently higher than normal to trip out overload circuit breakers there is still danger of tube failure because the overload, although of shorter duration, is increased in severity.

To remove this danger of tube failure while still retaining most of the advantages of grid leak bias, is a further object of my present invention and to fulfill it I employ sufficient fixed bias to protect the tubes in case their excitation fails and obtain the remainder of the required biasing potential from grid leak resistances in series with the fixed bias.

Still another feature, according to my present invention, which I employ to make the relative excitation and bias potentials, and therefore the amplification, more independent of power supply variation is to obtain both the anode and grid bias direct current potentials from rectifiers deriving their power from the same supply. I also use sufficient excitation on each stage to cause power limiting so that a variation in excitation causes relatively small change in output. Under these conditions a change in power voltage causes

changes in anode and grid potentials which tend to compensate one another and the unbalanced part of the variation is still further reduced by the limiting.

5 In accordance with United States Patent Office procedure my invention is defined in the appended claims. However, it may best be understood, both as to its structural organization and mode of operation, by referring to the accompanying drawings, wherein,

10 Figure 1 is a block diagram of a commercial transmitter built in accordance with my present invention,

15 Figure 2 is a schematic circuit diagram of the apparatus used in Figure 1,

20 Figure 3 is a block diagram of another transmitter adapted for commercial use built in accordance with my present invention,

25 Figures 4 and 4a schematically illustrate a circuit arrangement used in the apparatus shown in Figure 3,

30 Figure 5 is a block diagram of another form of commercial transmitter embodying my invention,

35 Figure 5a is a diagram or table indicating a few of the many combinations of an amplifier and a frequency multiplier amplifier which may be used in the arrangement shown in Figure 5,

40 Figure 6 is a circuit diagram of the apparatus blocked out in Figure 5, and,

45 Figures 7 and 8 are schematic wiring diagrams of transmitters devised in accordance with the present invention.

50 Referring to Figure 1 I have blocked out a transmitter wherein a crystal controlled oscillator 2 supplies energy to an amplifier and frequency doubler 4. Both the crystal controlled oscillator and amplifier frequency multiplier 4 are placed within a shielding compartment 6.

55 In accordance with the present invention, if it is desired to use higher frequency energy than that supplied by the frequency multiplier 4, an additional amplifier and frequency multiplier 8 is provided. The amplifier and frequency multiplier 8, as indicated, is of larger size and rating than the frequency multiplier and amplifier 4 so that substantial amplification besides frequency multiplication occurs in apparatus 8. If the output of apparatus 8 is of the correct frequency, it may be further amplified by a suitable amplifier 10 preferably of the pushpull type placed within a shielded compartment 12 with frequency multiplier-amplifier 8, and the output of amplifier 10 may be further amplified by an additional amplifier 12 placed in a shielding compartment 14, the output of the latter being fed, as indicated, to an antenna or other suitable utilization circuit.

60 As shown more fully in Figure 2, the crystal controlled oscillator or electron discharge device has coupled to its input electrodes a frequency controlling crystal 16 and has a tunable circuit 18 in its output circuit adjusted substantially to resonate at the fundamental frequency of the crystal. Energy from the output circuit of electron discharge device 2 is fed through a suitable blocking condenser 20 to frequency multiplier and amplifier 4 having an output circuit 22 tuned to a harmonic of the input frequency and, as indicated, tuned to the second harmonic (2f) of the fundamental (f).

65 Energy from the output circuit 22 is fed through blocking condenser 24 to frequency multiplier and amplifier 8 of larger size and rating than tube 4, the tube 8 having in its output circuit, a tunable circuit 26 tuned to the fourth harmonic (4f) of the fundamental, from which energy is fed to the

pushpull amplifier 10 through the tunable input circuit 28 thereof tuned to the fourth harmonic. I prefer to use a single tube frequency multiplier and amplifier followed by a pushpull amplifier stage for amplifying the output of the frequency multiplier, as a single tube frequency multiplier is more readily adjusted than a frequency multiplier of the pushpull type such as disclosed in my Patent 1,878,308, although, if desired, a pushpull frequency multiplier may be used in place of 10 a single tube frequency multiplier.

15 In any event the grid electrode of each tube acting as a combined amplifier and frequency multiplier is operated at a certain predetermined negative voltage such that when optimum anode potential is applied, plate current flows only during a brief portion of the duration of the positive cycle of input potential. Under these conditions the power output of the tube is almost as great at the lower harmonic frequencies as at the fundamental frequency. This operation has been 20 pointed out in considerable detail in my Patent #1,878,308, mentioned above, and the brief description given above is believed to suffice for 25 this application.

The output circuit 30 of amplifier 10 is tuned preferably to the fourth harmonic, and, the amplifier itself is neutralized as shown to prevent parasitic oscillation generation.

30 Output energy from the output circuit 30 may 30 then be fed through blocking condensers 32 to the tunable input circuit 34 of pushpull connected amplifier 12, also neutralized and also having a tunable output circuit 36 from which energy may be fed through suitable transmission lines 38 to 35 a radiating antenna 40.

35 The action and use of chokes 42 and high frequency by-passing condensers 44 are well known in the art and need not be discussed in detail here. Similarly, the use of such chokes, as chokes 40 46, voltage dropping resistor 47, and by-passing condensers 49, are sufficiently well known in the art so as not to warrant, as already indicated, added comment.

40 In practice, it is preferred that the transmitter be divided into, as shown, three separate compartments 6, 13, 14, properly shielded to reduce feed back of radio frequency energy. For this purpose it is preferable that no more than a single amplifier, that is, an amplifier in which 45 there is no frequency multiplication, be placed in any single compartment of the shielding.

45 The cathode energizing sources of the various electron discharge devices or tubes have been 50 omitted for the sake of simplicity but they may be of the alternating or direct current type, or a combination of the two. Thus, for example, it may be found desirable to supply unidirectional current to the cathodes of the oscillator and first frequency multiplier and amplifier 4, and, for the 55 remaining tubes of the system, alternating currents may be supplied to their respective cathodes for energization purposes.

55 The grid potentials for tubes 2, 4, 8 and 10 may be derived from potentiometer 52 grounded intermediate its ends by connection 54 and supplied with unidirectional potential from a rectifier 56, in turn deriving alternating energizing energy 60 through lines 58 from source 60. Anode biasing potentials for tubes 2 and 4 may also be derived from potentiometer 52, but, the anode potentials for frequency multiplier and amplifier 8 and pushpull amplifier 10 are preferably derived from a 65 separate rectifier 62 energized with three phase 70 75

alternating currents through lines 64 from source 60. Preferably, a separate rectifier 66 also energized from source 60 is used to supply anode potential to pushpull connected amplifier 12.

It is to be noted, that deriving the biasing and anode potentials from a single source 60 renders the amplification of the entire system more nearly constant and independent of power supply fluctuations. For, with variations in voltage from source 60 there will be corresponding variations of grid and anode biasing potentials in all of the tubes, and consequently, in the event of say, increased voltage for some reason or other from source 60, negative grid bias as well as positive anode bias will be increased thereby tending to keep the relative potentials adjusted for optimum efficiency at all times.

It is to be noted that grid leak arrangements in the form of condensers 50 and resistances 48 are used for the tubes. This is advantageous for the reason that should, for any reason, the radio frequency output from any stage vary above or below normal during operation, the bias on the succeeding stage is correspondingly altered to maintain output from the succeeding stage more nearly constant. However, to depend upon condenser and grid leak bias alone for the tubes would be dangerous to the tubes in the event of failure of radio frequency input. Under such conditions, there would be a tendency for a strong unidirectional anode current flow and this would tend to cause rapid destruction of the tube due to high anode currents. Simple overload protective devices placed in the unidirectional energy leads will not prevent ruin of the tubes under such circumstances inasmuch as the unidirectional current drawn may not exceed that during normal operation of the apparatus, but, the energy dissipation in the tubes is greatly increased due to the loss of high frequency output. Therefore, the loss of radio frequency input to one of the stages and, the flow of normal unidirectional current therethrough, would require a high energy dissipation in the tubes because of the loss of output.

To remove the danger of this possibility while retaining the advantages of grid leak bias, it is to be noted that the various grids are connected through conductors such as conductors 68, 70 and 72 to potentiometer 52 wherefrom sufficient fixed bias is obtained to protect the tubes involved in the event that their input excitation fails. During high frequency operation, of course, the added negative biasing potential required is supplied by the grid leak and condenser arrangements 48, 50.

In order to transmit code signals on the transmitter shown in Figure 2, a remotely controlled electromagnetic relay 74 having a movable armature 76 is provided. In the upper position of the armature 76, the grid bias leads of tubes 10 are connected to a relatively low negative potential point on potentiometer 52, thereby rendering the pushpull connected amplifiers conductive and thereby causing radiation of high frequency energy from the antenna 40. For stopping the signal energy, the armature 76 is moved to its lower position whereby the grids of tubes 10 are connected to a high negative point on the potentiometer 52 through resistance 78 and their anode currents are stopped, preventing amplification and delivery of power to the antenna. In this manner the oscillator 2 is allowed to oscillate continuously, and, the interposition of tubes 4, 8 prevents the varying loads from making themselves manifest upon the oscillator, thereby as-

sisting in constant frequency operation of the oscillator tube 2.

Of course, if desired, the system shown in Figure 2 may be modulated by telephone signals, in which case, various known arrangements may be used. Moreover, it is not necessary that rectifier 56 be of the three phase type, but, if found suitable, a single phase rectifier may be used, and connected across a single phase of the supply source 60.

If desired, the anode potential of tubes 10 may be simultaneously reduced with the increased bias on the grids thereof in a manner similar to the modulation scheme involving tubes 232 and resistance 236 of Figure 6, a similar relay such as 74 appropriately controlling the grid potentials on the tubes 232. It is to be understood, of course, that any combination of modulation schemes may be used such as the simultaneous variation in grid bias on tubes 10, and for example, the simultaneous variation in plate potential on frequency multiplier 4. These various combinations will, of course, suggest themselves as a reading of the specification is continued.

Figures 3, 4 and 4a illustrate another form of transmitter especially adapted for long distance communication work wherein, Figure 3 is a block diagram of the transmitter, and Figures 4 and 4a are wiring diagrams of the more important elements of the transmitter shown schematically in Figure 3. As shown in Figure 3, the transmitter comprises a crystal controlled oscillator 80 followed by buffer or shock absorbing amplifier 82, two frequency multiplier stages 84, 86, the latter also being used as a modulator and both multipliers being used preferably as frequency doublers. Another stage 88 adapted to be used as a simple amplifier or, as indicated as a frequency tripler, and, a final amplifier stage 90 are provided. As indicated, the crystal controlled oscillator 80, buffer amplifier 82, and first frequency multiplier 84, may be placed safely within a single shielding compartment 92 without fear of parasitic oscillation generation, and similarly the stages 86, 88 may be placed in another separate shielding compartment 94. The final amplifier stage 90 should, of course, be placed with an individual shielded compartment 96. Inasmuch as shielding is well known in the art, a further description of it is unnecessary here.

The tube sizes indicated in Figure 3, and also in Figure 1, are given merely by way of example and are not to be construed in any way limitative of the present invention. Attention is directed in particular to the second frequency multiplier 86 and amplifier 88, which is of much larger size and rating than frequency multiplier and amplifier 84, or amplifier 82. As a result of this construction, according to the present invention, a considerable amount of amplification of the energy is produced in the frequency multiplier, which eliminates many of the amplifiers which would be necessary if, in accordance with prior practice, the frequency multipliers are all made of the same size and rating, such as that of stage 84 for example. And similarly, the frequency multiplier stage 88 is made considerably larger in size and rating than the prior stage 86 so that within the frequency multiplier 88 a considerable amount of amplification ensues. By the use of amplification within the stages 86, 88, as already indicated, a long chain of amplifiers, subject to parasitic oscillation and costly maintenance, for building up the energy to a value sufficient to operate power amplifier 90, is eliminated.

The arrangement shown in Figure 3 is illustrated in greater detail in Figure 4. Regeneratively coupled electron discharge device oscillator is frequency controlled by either crystal 88 or 5 100 by suitable actuation of coupling or switching arrangement 102 which couples either crystal capacitively to the input electrodes of oscillator 80. The purpose of using two crystals is, of course, to provide a space crystal or to vary the 10 final output of the transmitter.

The crystals preferably are temperature controlled by any suitable temperature controlling apparatus diagrammatically indicated within rectangle 104 energized with heating energy from 15 a suitable source 106.

The output circuit 103 is tuned substantially to the fundamental of the crystal placed in circuit with oscillator 80, and energy therein is fed through a blocking condenser 110 to a buffer 20 amplifier 82 having a tunable output circuit 112 tuned also to substantially the fundamental frequency. To prevent parasitic oscillation generation or self oscillation, the buffer oscillator may be neutralized by the use of a suitable neutralizing 25 condenser 114 as indicated, or, as illustrated in the transmitter shown in Figures 6 and 7 for example, tubes for that purpose may be made of the screen grid type. Similarly, for better control the crystal oscillator tube 80 may be of the 30 screen grid type or of any multi-electrode type. The buffer amplifier, of course, acts to maintain constant load on the crystal oscillator preventing variations in load from making themselves felt upon the electrodes of the oscillator 80.

35 Output energy appearing in tunable circuit 112 is fed to the input side of a first frequency multiplier, here indicated as a frequency doubler and amplifier 84, having a tunable output circuit 116 tuned to the second harmonic of the fundamental. As described in my Patent 1,878,308, 40 frequency multiplier and amplifier 84 may be regeneratively coupled by means of a condenser 118 for energy of harmonic frequencies, but degeneratively coupled for energy of the fundamental frequency so that presence of energy of the fundamental frequency in the output circuit of tube 84 is effectively eliminated or reduced to 45 a negligible value.

Output energy from the frequency doubler and 50 amplifier 84 is fed through conductor *a* to frequency multiplier-amplifier modulator 86 shown in Figure 4a. The output circuit of tube 86 is tuned substantially to the fourth harmonic of the fundamental and as illustrated is regeneratively connected for energy of the harmonic frequency 4f.

Keyed energy appearing in lines 122 may be used to remotely control the electromechanical relay 124 to alter the bias on the grid of tube 86 55 so that in its contacting position it will shift the grid voltage on tube 86 to such a value as to pass peaks of input current into the output circuit of tube 86 such that it is shock excited at the harmonic frequency as described more fully in my copending application just referred to. That is, in the closed position of relay 124, a less negative potential from conductor 126 coupled to a suitable source of potential or potentiometer 128, is applied to the grid of tube 86 through connections 130. In the relay open position, negative tapping point 132 biases the grid of tube 86 through resistance 134 to such an extent that no high frequency energy appears in the output circuit 136 of tube 86. In addition to the relay for controlling the transmitter there is provided 75

switch 123 by means of which the control may be transferred from relay 124 to the local telegraph key 125 for the use of the transmitter attendant.

Fourth harmonic signal modulated high frequency energy is fed inductively, as indicated, to lines 138 to the input electrodes of pushpull connected frequency amplifier or frequency multiplier and amplifier 88 for the complete action of which reference is again made to my Patent 10 #1,878,308. As shown, the stage 88 acts simply as an amplifier, but, when used as a frequency multiplier to produce energy three times that appearing in the input circuit 148 or energy of a frequency 12f, switches 142, 144 are moved to 15 their other position by uni-control means 146 so that a higher negative bias is applied to the grids of the pushpull connected tubes 88 and so that the portion of the output circuit 148 to the right of the dotted line 150, is cut out of circuit 20 or short circuited away from the output electrodes of tubes 88. Under such circumstances, the output circuit is composed of inductances 152, 154 and condenser 156, tuned to the twelfth harmonic of the fundamental as indicated. 25 With the inclusion of condensers 158 and inductance coil 160, the entire output circuit is, of course, tuned to 4f and the tubes 88 act as a simple amplifier.

When acting as a simple amplifier, output energy from the output circuit of tubes 88 is fed through blocking condensers 162 and lines 164 to the input side of the power amplifier 90. When acting as a frequency tripler or multiplier as indicated, output energy from tubes 88 is fed 35 inductively to secondary coil 166, to the lines 168 through blocking condensers 170 to the input side of the power amplifier 90.

As described in my Patent Number 1,751,996, 40 it is preferable that the output ends of the transmission lines 138, 164 and 168 are coupled to the respective input circuits such that the lines face a portion of the input circuit equivalent in value to the surge impedance of the line so that standing waves are not set up thereon.

45 The stage 90 or the tubes therein are almost always used, in order to obtain best overall efficiency for the entire transmitter, as a simple amplifier, provision being made to readily adjust the tuning of the amplifier to either one of the 50 frequencies which it is desired to amplify. Thus, a uni-control switching means 172 is provided which places low frequency coils 190 and 182 in the input and output circuits respectively of tubes 90, when stage 88 is used as an amplifier 55 for energy of the lower frequency. Under such circumstances also, the transmission line 178 to the short wave or low wave length antenna is grounded by switches 180 as indicated.

A reverse movement of controlling member 172 60 will act to short circuit the long wave coil 182 out of circuit by switch 184, and, the relatively longer wave antenna transmission line 196 will be grounded by the other position of switches 188. In the input circuit, the longer wave coil 65 190 will be removed from circuit, and, the shorter wave coil 174 will be placed in the circuit by the reverse setting of switch 172.

This uni-control arrangement for rapid change-over in amplifier frequency is more fully 70 described and claimed in my copending application, Serial Number 189,162, filed May 5, 1927.

To prevent parasitic oscillation generation, the power amplifier tubes 90 are neutralized by condensers 194 cross-connecting the terminals of 75

the input and output tuning condensers 196, 198 respectively.

As indicated, the cathodes of the various tubes may be energized by alternating currents. Unidirectional potentials for the potentiometers and the various unidirectional supply leads indicated in Figures 4 and 4a, may be obtained from separate rectifiers as found necessary, but, in accordance with the present invention it is preferred that the separate rectifiers be energized from a single alternating current source whereby there is less tendency for changes in amplification with changes in supplied alternating voltages as would be the case where various rectifiers are supplied from different alternating sources.

Figure 5 is a block diagram of still another form of transmitter, the sizes of the tubes given being merely suggested and not in any way to be considered as limiting or binding the present invention thereto. The table shown in Figure 5a adjoining Figure 5, indicates a few of the many combinations of an ordinary amplifier and frequency multiplier which may be used in the arrangement shown in Figure 5. It is to be noted that wherever frequency multiplication occurs, the size and rating of the frequency multiplier are larger than the size and rating of a preceding amplifier tube. In this manner, as already thoroughly brought out hereinbefore, there is a considerable saving in the number of amplifiers required relative to arrangements heretofore known in the art. Preferably, in the arrangement shown in Figure 5 screen grid tubes are used rather than resort to neutralization for the prevention of parasitic oscillations. In addition, the use of screen grid tubes allows of better control and especially so in the case of the frequency multipliers. In this arrangement also, each stage is separately shielded, and, the circuits may be so arranged that each of the stages may be used for amplification either with or without frequency multiplication.

In practice many combinations of ordinary amplifiers and frequency multipliers may be used depending upon desired constructional requirements and the final value of frequency desired. Moreover, in this transmitter any stage may be used as an ordinary amplifier or as a frequency multiplier, and, if from the standpoint of power efficiency, the amount of frequency multiplication in any one stage is limited to tripling, and the last stage is always used as an ordinary amplifier, there are two-hundred and forty three (243) possible combinations of amplifier and frequency multiplication which may be used in the transmitter shown in Figure 5 without any change in the circuit arrangements.

Turning to Figure 6, the circuit diagram for the transmitter blocked out in Figure 5, an electron discharge device crystal controlled oscillator 200 supplies energy from its output circuit 202 of fundamental frequency f to a buffer amplifier 204 preferably of the screen grid type. Fundamental frequency energy f is fed from the output circuit 206 and buffer amplifier 204 to frequency multiplier and amplifier 208 whose output circuit 210 is tuned to the second harmonic $2f$. Energy from output circuit 210 of second harmonic frequency is fed to a further amplifier 212 which in turn, supplies amplified energy to a frequency multiplier and amplifier 214 of larger size and rating than preceding amplifier 212. By connecting coil 216 to the output circuit of tube 214, the output circuit will

be tuned to a frequency $4f$, and, by connecting coil 218 to the output circuit of the tube 214, the output circuit thereof will be tuned to a frequency $8f$, in which case a slightly higher negative bias should be imparted to the grid adjacent the cathode of tube 214 to cause more efficient transformation of energy in its input circuit of the frequency $2f$ to energy three times that in its output circuit.

The pushpull connected screen grid tube stage 218 may be used as an ordinary amplifier for amplifying the output from frequency multiplier and amplifier 214, or, when supplied with energy at its input side of a frequency $8f$, its high frequency output coil 220 may be placed in the circuit whereby the pushpull connected tubes 218 act as a frequency multiplier further multiplying frequency to a value sixteen times the fundamental frequency supplied by the crystal controlled oscillator. The output of stage 218 may then be fed to the four tubes 222, 224, tubes 222 and tubes 224 being connected in parallel, and the parallelly connected tubes being connected in pushpull fashion and neutralized as shown for the use of suitable neutralizing condensers 226. Suitable connection may then be made to the output coil 228 by transmission lines 230 to energize suitable antennæ (not shown).

Modulation may be accomplished by the use of parallelly connected tubes 232 supplied at their input side with signaling potentials from transformer 234. Consequently, by virtue of the connection of impedance 236 in the anode supply lead furnishing anode potential to tubes 232 and amplifier 212, the potential supplied to amplifier 212 will vary inversely to the current drawn by the modulating tubes 232 as a result of which modulated currents will appear in the output circuit of amplifier 212, which are further acted upon by the following frequency multipliers and amplifiers before radiation over the antenna. Of course, modulation may be accomplished by connecting conductors 238 to any one of the anode supply leads of the tubes shown, or, to any of the screen grids of the tubes and in practice the stage selected depends chiefly upon the character of the modulation. If the modulation is for telephone purposes it will usually be introduced in the anode or screen grid supply leads to stage 218 in order to obtain more faithful reproduction. If the modulation consists of telegraph keying only, or keying and tone modulation, it will usually be introduced in some earlier stage such as 214 or 212 because these early stages require less modulating energy and potential. In the figure no arrangement for keying is shown but it is intended that tubes 232 serve this purpose also by having superimposed upon the alternating current from transformer 234 to the grids, suitable direct current potential variations by means of a relay or vacuum tubes which are not shown in the drawings. If desired the modulation of the grids of the modulator tubes may consist only of direct current fluctuations in accordance with keying by telegraphic code. This will usually be the case where continuous wave telegraphy is desired.

The final power amplifier stage comprising tubes 222 and 224 may, of course, be of the screen grid type if desired, and, it should be clearly understood that any of the tubes in any of the systems shown may have a still greater number of electrodes, if found desirable.

Figure 7 is a circuit diagram of another trans-

mitter which may be built in accordance with the principles of the present invention. Energy of fundamental frequency f is fed from a crystal controlled oscillator 240 to a screen grid electron discharge device frequency multiplier and amplifier 242. Modulation is introduced into its stage by the action of transformer 244 which algebraically adds modulation potentials to the unidirectional potentials supplied to the anode of tube 242. Tube 242 is followed by a further frequency multiplier and amplifier 246 of larger size and rating than any of the preceding tubes 240, 242 which supplies energy of multiplied frequency to the pushpull connected screen grid amplifier 248 whose output, as shown, is directly radiated from a suitable antenna 250.

In Figure 8, modulation is introduced to the screen grid of a frequency multiplier 252 following a crystal controlled oscillator 254 and pushpull connected amplifier 256. Depending upon signaling potentials introduced by transformer 258, variable currents are drawn by modulator tube 260 connected across rectifier 262 in series with resistance 264 whereby, the positive potential applied to the screen grid of tube 252 is varied inversely to the current drawn by tube 260. The modulated frequency multiplied energy from frequency multiplier-amplifier modulator 252, is fed to a pushpull connected amplifier 266 whose output is further frequency multiplied and amplified by a single tube screen grid frequency multiplier tube 268. The output of the latter tube is further amplified by pushpull connected amplifier 270 energizing antenna 272 with the amplified frequency multiplied and modulated high frequency energy.

As previously explained in connection with Figure 6 it is to be understood that the modulation scheme shown in Figures 7 and 8 may have many modifications depending upon the character of modulation desired and the characteristics of the various parts brought together to form the complete transmitter. Thus the modulation may be introduced on the anodes, screen grids or control grids of any stage depending upon the results desired and telegraphic, facsimile, or other keying may be introduced at the same or different points. The circuits shown are merely examples of a few of the combinations in which my invention may be used.

In the arrangement shown in Figure 8, it should be noted that for the sake of simplicity, the neutralizing connections have been omitted from the pushpull connected amplifiers, which, if desired, may be made of the screen grid type, and which are alternated with single tube frequency multipliers and amplifiers of sufficient size and rating to introduce appreciable amplification as well as frequency multiplication of the output of the preceding pushpull connected amplifier.

It would be impractical to illustrate and describe all of the various modifications of the present invention which would readily suggest themselves to those skilled in the art. Consequently it is to be clearly understood that the present invention is not to be limited by the few examples given in the attached drawings, but is to be given the full scope and width indicated in the appended claims.

Having thus described my invention, what I claim is:

1. In combination, a crystal controlled oscillator including a thermionic discharge device, a frequency multiplier comprising a second single electron discharge device of larger size and rating

than the discharge device of said oscillator coupled to the output of said oscillator for frequency multiplying and amplifying the oscillations produced thereby, a pair of pushpull connected electron discharge devices coupled to the output of said last named amplifying and frequency multiplying device and arranged to simultaneously frequency multiply and amplify the oscillations of said frequency multiplier, and a second pair of pushpull connected electron discharge devices coupled to the output of said last named pair of tubes and arranged to amplify the output of said pushpull connected frequency multiplier and amplifier arrangement of electron discharge devices, whereby oscillations of considerable frequency and amplitude are obtained with a minimum amount of apparatus.

2. In high frequency signaling apparatus, the combination of a crystal controlled master oscillator of the thermionic type, a single tube combined frequency multiplier and amplifier, a circuit tuned to the frequency of the master oscillator interposed between the master oscillator and the frequency multiplier for coupling the latter to the former, and an output circuit for said amplifier and multiplier tuned to some multiple of the frequency of said tuned coupling circuit, whereby said second named tube frequency multiplies and amplifies the output of said master oscillator, a second single tube combined frequency multiplier and amplifier of larger size and rating than said first mentioned frequency multiplier and amplifier, a circuit tuned to the frequency of the output of said first mentioned combined frequency multiplier and amplifier interposed between said combined frequency multipliers and amplifiers, and an output circuit for said last mentioned combined multiplier and amplifier tuned to a multiple of the frequency of said last named tuned circuit whereby said last named combined multiplier and amplifier multiplies and amplifies the output of said first mentioned frequency multiplier and amplifier, an amplifier for amplifying the output of said last mentioned combined frequency multiplier and amplifier, and, an antenna coupled to said amplifier.

3. In high frequency electrical apparatus, the combination of a master oscillator of the crystal controlled thermionic type, a pushpull amplifier of the thermionic type having its input electrodes coupled to the output electrodes of said oscillator for amplifying the oscillations produced thereby, a single tube combined frequency multiplier and amplifier having its input electrodes coupled to the output of said pushpull amplifier, a pushpull amplifier of the thermionic type having its input electrodes coupled to the output electrodes of said last named combined frequency multiplier and amplifier for amplifying the oscillations in the output of said combined frequency multiplier and amplifier, a single tube combined frequency multiplier and amplifier of larger size and higher rating than the preceding tubes coupled to the output of said last mentioned pushpull amplifier, a pushpull amplifier coupled to the output of said last named tube for amplifying the oscillations in the output of said last mentioned combined frequency multiplier and amplifier, and a load circuit coupled to the output of said last mentioned pushpull amplifier, each of said single tube combined frequency multipliers and amplifiers having an anode, a cathode, a plurality of auxiliary electrodes, an input circuit tuned to a predetermined frequency, and an output circuit tuned to a

multiple of that frequency, whereby high frequency oscillations of considerable amplitude are produced with minimum apparatus and reaction between successive stages is prevented.

5. In combination, a high frequency electrical signaling apparatus, a master oscillator of the thermionic type, an efficient means for increasing the amplitude and frequency of the oscillations in said oscillator comprising, a plurality of combined frequency multipliers and amplifiers successively coupled together, successive combined frequency multipliers and amplifiers being of larger size and rating than prior combined frequency multipliers and amplifiers, and an output circuit for the last mentioned combined frequency multiplier and amplifier, one or more of the tubes of said frequency multipliers and amplifiers having a screen grid therein to insure stable operation of said apparatus.

20. 5. In apparatus for transmitting high frequency undulatory electrical currents, a control oscillator, an electron discharge device combined frequency multiplier and amplifier coupled to said control oscillator, an electron discharge device amplifier coupled to said combined frequency multiplier and amplifier for amplifying energy from said combined frequency multiplier and amplifier, a rectifier for supplying anode potential to said combined frequency multiplier and amplifier, another rectifier for supplying anode potential to said electron discharge device amplifier, and a single source of alternating energy for energizing said rectifier, whereby efficient and stable operation with a minimum amount of apparatus is obtained.

40. 6. In apparatus for relaying undulatory high frequency electrical currents, an electron discharge device having within an evacuated container, an anode a cathode and a grid, a potentiometer subjected to substantially unidirectional potentials, a connection between a point on said potentiometer and said cathode, a connection between a point on said potentiometer, which is negative relative to said first named point, and said grid, a resistance in series in one of said connections, whereby in the presence of high frequency potentials applied to said grid appreciable grid current flows and said grid is maintained at a desired unidirectional potential, by the drop in potential through said resistance, and, in the absence of said high frequency potentials and appreciable grid current, the potential derived from said potentiometer is sufficient to prevent unduly high unidirectional currents from flowing to the anode of said electron discharge device, a high frequency choking inductance in said connection, and a high frequency bypass condenser connected in shunt with said resistance and that portion of the potentiometer between said cathode and said grid.

55. 7. In apparatus for undulatory electrical currents, an electron discharge device oscillator, an electron discharge device combined frequency multiplier and amplifier coupled to said oscillator for simultaneously amplifying and frequency multiplying energy from said oscillator, said electron discharge device frequency multiplier having within its evacuated container an anode a cathode a control grid and a screen grid which insures stable operation of said device, and means for subjecting said screen grid to modulating potentials whereby in the output circuit of said frequency multiplier there appears signal modulated frequency multiplied energy.

75. 8. In a system for transmitting intelligence

from one geographically situated point to another by propagated electro-magnetic waves derived from the flow of undulatory high frequency electrical energy operated upon in accordance with the intelligence to be transmitted, amplifying apparatus for obtaining improved stability and freedom from parasitic oscillations comprising a chain of successive alternating current amplifier stages, circuits for capacity neutralizing one or more of the stages whereby coupling between input and output circuits thereof is eliminated, means for obtaining frequency multiplication of alternating currents in one or more of the amplifier stages, and means for protecting said tubes from overload including circuits for applying a bias between the control grids and cathodes which is determined in part by a fixed source and in part by the amplitude of the signal impressed on the respective control grids.

9. In a system of the character described having a chain of alternating current electron discharge device amplifiers and combined amplifiers and frequency multipliers, the method of improving the stability and freedom from the effects of power supply voltage variations of said apparatus during operation which includes, applying input energy of such magnitude to one of the stages so that limiting ensues whereby variations in strength of the input energy produces relatively little variation in strength of the output energy of that stage, and simultaneously amplifying and frequency multiplying the energy resulting from said limiting action.

10. In apparatus of the character described, a crystal controlled electron discharge device oscillator producing energy of a fundamental frequency, a single tube electron discharge device frequency multiplier and amplifier for combined frequency multiplying and amplifying the energy from said oscillator of fundamental frequency, a pushpull arrangement of electron discharge devices for simultaneously frequency multiplying and amplifying the output of said single tube combined frequency multiplier and amplifier, and a pushpull arrangement of electron discharge devices coupled to said pushpull frequency multiplier, for amplifying the frequency multiplied energy from said pushpull connected electron discharge device frequency multiplier.

11. In high frequency electrical apparatus, the combination of a master oscillator of the crystal controlled thermionic type, a thermionic amplifier coupled thereto for amplifying the oscillations produced by said oscillator, a combined frequency multiplier and amplifier including a single tube coupled to said first named amplifier, a second combined frequency multiplier and amplifier including a single tube coupled to said last mentioned combined frequency multiplier and amplifier, and an additional thermionic stage including a thermionic tube having an input circuit coupled to the output of said last named combined frequency multiplier and amplifier, the tubes in each of said stages being of a size greater than the tube in preceding stages, and means whereby said last named stage may be operated as an amplifier or as a frequency multiplier including, an output circuit comprising tuning reactances coupled to the output electrode of said last named tube, and switching means for changing the reactances in said output circuit.

12. In high frequency electrical apparatus, the combination of a master oscillator of the crystal

controlled thermionic type, a thermionic amplifier coupled thereto for amplifying the oscillations produced by said oscillator, a combined frequency multiplier and amplifier including a single tube coupled to said first named amplifier, a second combined frequency multiplier and amplifier including a single tube coupled to said last mentioned combined frequency multiplier and amplifier, an additional thermionic stage including a thermionic tube having an input circuit coupled to the output of said last named combined frequency multiplier and amplifier, the tubes in each of said stages being of a size greater than the tube in preceding stages, means whereby said last named stage may be operated as an amplifier or as a frequency multiplier including, an output circuit comprising tuning reactances coupled to the output electrode of said last named tube and switching means for changing the reactances in said output circuit, means for applying biasing potentials to the control grids of all of said tubes, and switching means for changing the value of the biasing potentials applied to the control grid of the tube in said last named stage when the reactance in the output circuit of said stage is changed.

13. In a high frequency electrical apparatus, the combination of a master oscillator of the crystal controlled thermionic type, a thermionic amplifier coupled thereto for amplifying the oscillations produced by said oscillator, a combined frequency multiplier and amplifier including a single tube coupled to said first named amplifier, a third amplifier stage including a single tube coupled to said last mentioned combined frequency multiplier and amplifier, an additional combined frequency multiplier and amplifier stage including a thermionic tube having an input circuit coupled to the output of said last named combined frequency multiplier and amplifier, the tubes in each of said stages being of a size greater than the tube in the preceding stage, a fifth thermionic stage having its input coupled to the output of said additional thermionic stage, said fifth thermionic stage comprising, a pair of thermionic tubes having input electrodes and output electrodes, a plurality of input circuits normally resonant at different frequencies, a plurality of output circuits normally resonant at different frequencies, and switching means for coupling predetermined sets of said

input and output circuits to said input and output electrodes, whereby said last named stage amplifies the oscillations impressed on the input of the preceding stage coupled to said last named stage either at the fundamental frequency or a harmonic thereof. 5

14. In electrical apparatus of the character described, a control oscillator, a combined frequency multiplier and amplifier of the thermionic type coupled to said oscillator for simultaneously amplifying and frequency multiplying energy derived from said oscillator, a pair of pushpull connected electron discharge devices coupled to said amplifier for frequency multiplying and amplifying the frequency multiplied energy derived 10 from said frequency multiplier and amplifier, a source of fixed potential connected between the grid and cathode of each of said tubes, and means for superimposing an additional bias on each of said fixed biases including a resistance in 15 series in each of said connections.

15. A signalling system including an oscillation generator comprising a thermionic tube having a control grid connected in a frequency determining circuit, including a piezo-electric crystal, 25 said tube also including an anode and a cathode, a circuit connected to said anode and cathode of said tube, means to tune said circuit to the frequency at which said crystal tends to oscillate due to the stored wave energy therein, an amplifying device comprising a second thermionic tube having anode, cathode and control grid, a reactance coupling said control grid to the tunable output circuit of said oscillator tube, a tunable circuit coupled between the anode and cathode 30 of said second named tube, an amplifying and frequency multiplying device comprising a third thermionic tube of greater power rating than said second named tube, said third named tube having an anode, cathode and control grid, a device coupling the control grid of said third named tube to the tunable circuit connected to the anode of said second named tube, an amplifier comprising a fourth thermionic tube of greater 35 power rating than said third named tube, said last named tube having anode, cathode and control grid, a reactance coupling the control grid of said fourth named tube to the anode of said third named tube, and a work circuit coupled to the anode of said fourth named tube. 40 45 50

CLARENCE W. HANSELL.
